UNITED STATES PATENT OFFICE

2,571,177

POWER SWUNG LOG TURNER

James B. Allen, Prineville, Oreg.

Application January 12, 1948, Serial No. 1,871

1 Claim. (Cl. 143—97)

1

The present invention relates to new and useful improvements in log turners for sawmills and more particularly to a power operated saw turner adapted to turn a log while resting upon a saw carriage and thus relieve the operator of manual effort and danger of turning the logs.

An important object of the invention is to provide a log turner which includes a vertically movable bar having a plurality of vertically spaced log engaging teeth to effect the turning movements of the log on its carriage together with means for raising and lowering the bar as well as means for bringing the upper end of the bar into and out of position for engaging the logs.

A still further object is to provide an apparatus of this character of simple and practical construction, which is efficient and reliable in operation, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a top plan view.

Figure 3 is a fragmentary transverse sectional view taken substantially on a line 3—3 of Figure 2.

Figure 4 is a side elevational view of a modified construction illustrating hydraulic operating means for the device and with parts broken away and shown in section.

Figure 5 is a top plan view, and

Figure 6 is a front elevational view.

Referring now to the drawings in detail and first with respect to the form of the invention illustrated in Figures 1 to 3 inclusive the numeral 5 designates a substantially rectangular shaped frame having a transverse shaft 6 journaled in bearing brackets 7 at the front end of the frame and on which the lower end of a channel shaped post 8 is pivotally mounted for forward and rearward swinging movement.

The shaft 6 is provided with a pair of crank arms 9 to which the lower end of a connecting rod 10 is attached by means of a wrist pin 11, the connecting rod extending upwardly in the post 8 and pivoted at its upper end to a vertical log turning bar 12 slidably mounted in the post 8. The edges of the post are formed with the in-turned flanges 13 to retain the bar 12 in position

2

therein during its vertical reciprocating movement.

The upper front edge of the bar 12 is provided with an upper fishtail shaped tooth 14 and a lower upwardly inclined tooth 15 for biting into a log carried by a saw table to effect a turning movement of the log by the raising and lowering of the bar 12.

The shaft 6 is driven by means of a pair of sprockets 16 secured to the ends of the shaft and driven by chains 17 from a pair of sprockets 18 secured to the ends of a transverse shaft 19 journaled in bearing brackets 20 secured to the frame 5 at a point rearwardly of post 8.

The shaft 19 is driven by a pulley 21 secured to one end of shaft 19 and belt 22 driven by a reduction pulley 23 secured to one end of a transverse shaft 24 journaled in bearing brackets 25 carried by the frame, the other end of shaft 24 having a pulley 26 secured thereto driven by a belt 27 from a suitable source of power.

The upper ends of bar 12 and post 8 are moved forwardly and rearwardly into and out of engaging position with the log by means of a nigger bar 28 pivoted at its upper end to the post and connected at its lower end to an eccentric 29 driven by a transverse shaft 30 journaled in bearing brackets 31 secured to the rear portion of frame 5. The shaft 30 is driven by a sprocket 32 secured thereto and chain 33 from a sprocket 34 secured to the shaft 19.

Also secured to shaft 30 is a ratchet 35 engaged by a pivoted pawl 36 mounted on the frame to hold the bar 12 and post 8 in a forward position.

In the form of the invention illustrated in Figures 4 to 6 inclusive the supporting frame is shown at 37 to which the lower end of post 38 is pivoted by a transverse pin 39.

A bar 40 is mounted in post 38 for vertical reciprocating movement as heretofore described and is provided with anti-friction rollers 41 travelling in the post.

A hydraulic cylinder 42 is positioned in the lower portion of post 38 and having a piston rod 43 extending upwardly therefrom pivoted to the lower end of bar 40. Fluid pressure supply and return lines 44 and 45 are connected to the cylinder.

A nigger bar 46 is also pivoted at its upper end to the post 38 and has its lower end working in a hydraulic cylinder 47 pivoted to the rear of frame 37 and also provided with supply and return lines 48 and 49.

In view of the foregoing description taken in conjunction with the accompanying drawings it

is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A log turning device for saw mills, said device comprising a base frame, a hollow vertical guide pivoted at its lower end to said frame, a reciprocatable log turning bar disposed in said guide, power operated means connected to the lower end of said bar for actuating said bar, said guide being provided with a longitudinal slot, means connected with said bar and located partially within said slot for swinging said guide and bar into and out of log-engaging position, the last-mentioned

means comprising an eccentric carried by said frame, a link connected with and operated by said eccentric, a bracket located in said slot and connected to said bar and having said link pivotally connected therewith, and said means for actuating said bar being operatively connected with said eccentric for actuating said eccentric.
